TISSUE ROLL DISPENSER

Hugh E. McCants, Houston, Tex.

Application May 12, 1955, Serial No. 35,953

Term of patent 14 years

(Cl. D4—3)

I claim:

The ornamental design for a tissue roll dispenser, substantially as shown.
